STOCK QUOTATION PROJECTING MACHINE

August D. Eitzen, Rockville Centre, N. Y., assignor to News Projection Corporation, New York, N. Y., a corporation of New York

Application October 16, 1931, Serial No. 569,128
Renewed August 8, 1934

13 Claims. (Cl. 178—42)

This invention relates to stock quotation projecting machines in general and more especially to stock quotation projecting machines associated with high speed motor driven tickers.

5 Among the objects of the present invention, it is aimed to provide an improved stock quotation projecting machine in which provision is made for causing the last printed quotation to be advanced into projecting position after the ticker 5 comes to rest so that such last printed quotation will not be concealed from view for a period longer than the period required ordinarily for a quotation to be advanced from the ticker to the light aperture.

10 15 It is still another object of the present invention to provide an improved stock quotation projecting machine in which the tape is caused continuously to be fed across the light aperture during the ordinary trading hours and yet the portion of the tape at the printing position be maintained at rest during the impression interval.

Specifically this invention aims to provide an improved stock quotation projecting machine contemplating the use of a high speed motor 25 driven ticker in which the tape is continuously fed across the light aperture at a uniform rate of speed and the portion of the tape passing the printing position during printing operation be intermittently advanced at a greater speed so as to permit the portion of the tape located at the printing position to be maintained at rest during the printing operation.

These and other features, capabilities and advantages of the invention will appear from the 35 subjoined detail description of one specific embodiment thereof illustrated in the accompanying drawings in which—

Figure 1 is a front elevation of a stock quotation projecting machine equipped according to the present invention;

Fig. 2 is a fragmental side elevation of the same part in section;

Fig. 3 is an enlarged detail view in end elevation of the tape feed actuating mechanism;

Fig. 4 is a side elevation of the tape feed actuating mechanism illustrated in Fig. 3 still further enlarged; and—

Fig. 5 is a fragmental detail in end elevation of a part of the tape feed actuating mechanism still further enlarged as compared to Fig. 4.

In the embodiment illustrated, the ticker 1 is shown as typical of the high speed motor driven variety recently adopted by the New York Stock Exchange showing the tape supply 2 in dotted line from which the tape T passes between the

type wheel 3 and the printing hammer 4 and then on to the initial tape feeding roller 5, then on to the second tape feeding roller 6, and then over the light aperture formed at the top of the extension 7 of the lamp housing 8 and then on to the rewind reel 9 mounted on the shaft 10 journaled in the bearing 11.

The shaft 10 is provided with a pulley 12 which is connected by the spring belt 13, the pulley 14 being mounted on the shaft 15 of the motor 16. 10 The type wheel 3, see Fig. 3 is associated with the type wheel stop unit 17 made according to a standard high speed motor driven ticker which is operatively connected to the shaft 18 on which is mounted the type wheel gear 19 in mesh with the motor pinion 20 mounted on the shaft 21 of the ticker motor 22. The motor pinion 20 also meshes with the main shaft gear 23 mounted on the shaft 24.

The shaft 24 has mounted thereon the motor 20 control pinion 25 in mesh with the motor control gear 26 which, see Fig. 4, meshes with the driven gear 27, part of the attachment now to be described.

Heretofore the secondary tape feed roller 6 25 was intermittently actuated. In the present embodiment, the intermittent actuating mechanism for this tape feeding roller 6 has been omitted and in place thereof, the attachment now described substituted.

This attachment includes a horizontally extending shaft 28 on the end of which the gear 27 is mounted. On the other end of such shaft, there is provided the beveled gear 29 in mesh with the beveled gear 30 at the upper end of the 35 shaft 31. At the lower end of the shaft 31, there is formed the beveled gear 32 in mesh with the beveled gear 33 mounted on the horizontally extending shaft 34, at the other end of which is mounted the tape feeding roller 6. 30

By this connecting mechanism, the tape feeding roller 6 will be continuously and uniformly operated whenever the motor 22 is operated. In addition to this continuous uniformly operating feeding roller 6, there is provided the feed roller 45 5 which is intermittently actuated, it being secured on the shaft 35 on which is mounted the clutch disk 36, the shaft 35 extending through the link 37, the upper end of which is pivotally connected to the link 38 which in turn is pivotally connected to the crank 39 secured at its upper end to the shaft 40 which in turn has fixed thereon the follower 41 provided with a cam roller 42 travelling in the cam groove 43 of the cam 55

44. The cam 44, see Fig. 3, is mounted on the shaft 24.

For pressing the tape T into friction engagement with the rollers 5 and 6, there are provided the pressure rollers 45 and 46 mounted on the brackets 47 and 48 respectively which are in turn pivotally mounted on the pivot pins 49 and 50 respectively, which brackets 47 and 48 are furthermore provided with the downward extensions 51 and 52 respectively which are connected by the spring 53 and 54 respectively resiliently to cause the pressure rollers 45 and 46 to press the tape T against the feed rollers 5 and 6 respectively.

15 The link 37 is provided with a recess 55 to receive the roller 56 resiliently urged against the inclined face 57 of the recess 55 by the spring 58, the roller 56 permitting the disk 36 freely to rotate with the feed roller 5 when the cam roller 20 42 is in the inner portion of the cam groove 43 and the face 57 frictionally engaging the cam roller 56 to cause the disk 36 to rotate in the reverse direction when the cam roller 42 rides in the outer portion of the cam groove 43. The cam 25 44 is so timed relative to the operation of the type wheel 3 that it will cause the tape T to advance the distance of a character and intervening space immediately before the printing action takes place.

30 This advancing action of the feed roller 5 will exceed in speed the advancing action of the feed roller 6 so as to cause the tape T to form a loop, see the dash and dot line 59 between the rollers 5 and 6 in Fig. 4, this slack 59 being sufficient so 35 that if a printing interval ensues, the portion of the tape T at the printing location will be maintained at rest and the continuously operated tape feeding roller 6 merely take up the slack 59 to maintain the continuous, uniform advancing action of the tape toward the light aperture without exercising any undue pulling strain on the tape during the printing interval. The slack 59 thus forms a reservoir or surplus to be drawn upon by the roller 6 during the printing impression. The cam 44 is mounted on the shaft 24 as 40 aforesaid to be driven only during a printing cycle so that this slack 59 is only formed during the transmission of a character or series of characters forming a message. When the transmission of a 45 message is completed and an interval elapses when no printing takes place, the roller 5 will be permitted to idle relative to the pressure roller 45 and the slack taken up in advance of the continuously operated tape feeding roller 6 so that 50 the roller 6 may advance the last printed quotation into the light aperture without delay so that the interval required for the last quotation to pass into the light aperture after the printing action comes to rest will merely equal the time 55 ordinarily required for such quotation to pass from the ticker or printing location of the ticker to the light aperture.

It is of course obvious that this intermittent feeding mechanism heretofore operatively connected to the cam 44 in advance of the type wheel 3 will be omitted and that the motion of the roller 5 is substantially identical with the motion of that intermittent feeding mechanism so omitted with the exception that the improved over- 60 running clutch consisting of the roller 56 in the notch 55 will allow a free drawing of the tape.

As will appear from Figs. 1 and 2, the light rays from the lamp 60 in the lamp housing will pass through the condensers 61 and 62 to the 65 deflector 63 from which they pass up through the

light aperture and tape to the objective lens contained in the housing 64 mounted in the bracket 65 extending from the upper end of the extension 7. The light rays then pass up to the deflector 66 by which they are deflected onto the deflector 5 67 and then deflected onto the screen 68 in the usual way.

It is obvious that various changes and modifications may be made to the details of construction without departing from the general spirit of the 10 invention as set forth in the appended claims.

I claim:

1. A high speed motor driven ticker having a motor, a tape-printing mechanism and a continuously operated tape feeding roller operatively connected to said motor, and acting upon said tape in the order named, and an intermittently operated tape feeding roller providing an expendable and constantly renewed slack in the printed portion of said tape in advance of the 20 continuously operated tape feeding roller during the transmission of a message and immediately preceding the actual impression.

2. A ticker having a motor, a continuously operated tape feeding roller operatively connected 25 to said motor, a printer, a second tape feeding roller disposed to engage the tape between the printer and the continuously operated tape feeding roller, said second tape feeding roller being normally idle, and means for actuating said second tape feeding roller to form slack in the tape in advance of said continuously operated tape feeding roller before the actuation of said printer to maintain the tape at rest during the printing 30 actuation of said printer.

3. A ticker having a main shaft, a motor control gear operatively connected to said main shaft, a continuously operated tape feeding roller operatively connected to said motor control gear, a cam on said main shaft, and an intermittently actuated tape feeding roller operatively connected to said cam, said intermittently operated tape feeding roller forming slack in the tape in advance of the continuously operated tape roller immediately preceding a printing action.

4. The combination with a ticker having a continuously operated tape feeding roller, and an intermittently operated tape feeding roller for forming slack in the tape in advance of the continuously operated tape feeding roller immediately preceding a printing action.

5. A ticker having a motor, a printer operatively connected to said motor, a main tape feeding roller, means for operatively connecting said main tape feeding roller to be continuously 55 operated by said motor, a secondary tape feeding roller disposed between said printer and said main tape feeding roller, and means for operatively connecting said secondary tape feeding roller to be operated by said motor to form slack in the 60 tape in advance of the main feeding roller so that the main feeding roller will take up the slack so formed.

6. The combination of a ticker having a printing mechanism, an intermittently operated tape 65 feeding roller, a continuously operated tape feeding roller, means for operating said second feeding roller at a uniform rate of speed, and means for actuating said first named feeding roller immediately before an impression of said printing 70 mechanism at a greater speed than that transmitted by said second feeding roller to impart a greater momentary velocity to the tape in turn to form slack in advance of said second feeding roller.

7. The combination of a ticker having a printing mechanism, an intermittently operated tape feeding roller, a continuously operated tape feeding roller, means for actuating said second feeding roller at a uniform rate of speed, and means for successively actuating said first named feeding roller and said printing mechanism to impart slack in the tape in advance of said first named feeding roller during an impression of said printing mechanism.

8. The combination with a ticker having a printing mechanism, an intermittently operated tape feeding mechanism, and means for successively actuating said printing mechanism and said tape feeding mechanism, of a continuously operated tape feeding mechanism, a tape pulling mechanism cooperating with said continuously operated tape feeding mechanism to draw the tape across the light aperture of a projecting machine, and control means for said intermittently operated tape feeding mechanism comprising a device for imparting a momentary greater feeding speed to the tape in advance of said continuously operated tape feeding mechanism and thereupon anchoring the same during the impression moment of said printing mechanism to permit the uniformly operated tape feeding mechanism merely to take up the slack formed between it and said uniformly operated tape feeding mechanism thereby to maintain at rest the tape portion being impressed during the printing operation.

9. The combination with a web marking device, of a continuously operated web feeding device, an intermittently operated web feeding device disposed to engage the web between the positions of contact with the web by said marking device and said continuously operated feeding device, means operatively associated with said web marking device for actuating said continuously operated web feeding device at a predetermined rate of speed, and means operatively associated with said marking device for momentarily actuating said intermittently operated web feeding device at a rate of speed faster than that imparted to the continuously operated web feeding device to relieve the portion of the web receiving an impression by said marking device from any pulling strain by said continuously operated feeding device.

10. The combination with a web marking device, of a continuously operated web feeding device, an intermittently operated web feeding device disposed to engage the web between the positions of contact with the web by said marking device and said continuously operated feeding device, means operatively associated with said web marking device for actuating said continuously operated web feeding device at a predetermined rate of speed.

5 determined rate of speed, and means for successively actuating said intermittently operated feeding device and said marking device, said intermittently operated feeding device being operated at a faster rate of speed than that imparted to said continuously operated feeding device and before said marking device is operated momentarily to arrest the portion of the web receiving a printing impression during the impression receiving interval.

10 11. The combination with a web marking device, of a continuously operated web feeding device, an intermittently operated web feeding device, means operatively associated with said web marking device for actuating said continuously operated web feeding device at a predetermined rate of speed, and means operatively associated with said web marking device for momentarily actuating said intermittently operated web feeding device at a rate of speed faster than 20 that imparted to the continuously operated web feeding device to relieve the portion of the web receiving an impression by said marking device from any pulling strain by said continuously operated feeding device.

25 12. The combination with a web marking device, of a continuously operated web feeding device, an intermittently operated web feeding device, means operatively associated with said web marking device for actuating said continuously 30 operated web feeding device at a predetermined rate of speed, and means for successively actuating said intermittently operated feeding device and said marking device, said intermittently operated feeding device being operated before said 35 marking device is operated momentarily to arrest the portion of the web receiving a printing impression during the impression receiving interval.

35 13. The combination with a web marking device, of a web feeding device, a second web feeding device disposed to engage the web between the positions of contact with the web by said marking device and by said first web feeding device, means operatively associated with said web 45 marking device for actuating said first web feeding device to impart a predetermined rate of feeding speed to the web, and means for successively actuating said second feeding device and said marking device, said second feeding 50 device being operated to impart a faster rate of feeding speed to the web than that imparted to the web by said first feeding device and being operated before said marking device is operated 55 momentarily to arrest the portion of the web receiving a printing impression during the impression receiving interval.

AUGUST D. EITZEN.
